HOWARD V. HARDING, OF NEW YORK, N. Y., ASSIGNOR TO PETER CLARK, INC., OF NEW YORK, N. Y., A CORPORATION OF NEW YORK.

VANISHING FOOTLIGHT FOR STAGES

Application filed September 18, 1928. Serial No. 306,772.

This invention relates to improvements in stages for theatres and more particularly to vanishing footlights for stages.

Objects

5 Among the principal objects which the invention has in view are:—To provide a stage construction whereby the footlights may be concealed beneath the stage when not in use 10 or brought above the stage into operative position for illumination when desired; to provide novel means for moving the footlights from one position to the other; to construct the stage to allow ready movement of the footlights and change from operative to inoperative 15 positions thereof; and generally to simplify, improve and perfect the structure and arrangement.

Drawings

20 Figure 1 is a side elevational view partly in section of a stage and vanishing footlights constructed in accordance with the present invention and showing the footlights in operative position for stage illumination;

25 Figure 2 is a similar view but with the footlights in inoperative position and concealed beneath the stage.

Description

30 In detail, the invention is embodied in a construction which comprises a stationary stage portion, 10, of customary character supported by suitable columns or struts, 11. The 35 forepart of the stage is provided with a well, 12, which is covered in part and at the rear by a movable stage section, 13, pivoted as at 14 to the stationary stage. The remainder of the well is covered by movable sections, 15 and 40 16. Section 15 is hinged to 16 as at 17 while the section 16 is pivoted as at 18 to the front of the stage. The hinge and pivot details may be of any desired or preferred characters in the practice of the invention, as these 45 details are not essential.

The footlights or electric light projectors, 19, are mounted on a movable frame, 20, which is attached to the bottom of section 15 so that frame, projectors and section move as 50 a unit. The frame, 20, is fastened to the ends

of links, 21, which are pivoted as at 22 to a support 23 on the stationary stage. The frame is adapted to swing on these links. A rocker arm, 24, is provided on a pivot shaft, 25, on a floor or base, 26, in the well and the 55 ends of the rocker arm have connecting rods, 27 and 28, fastened respectively to section, 13 and frame 20. The movements of the rocker arm may be obtained by rotation of pivot shaft, 25, as by an electric motor or similar 60 operating mechanism (not shown).

In the operation and functioning of the construction, the rocker arm may assume one of two positions, that of Figure 1 or that of Figure 2. In the first of these positions, Figure 1, the rear movable stage section 13 is lowered so as to slope or dip downward as in the old footlight gutter, the sections 15 and 16 are elevated with projectors 19 and supporting parts, and the projectors are in operative 70 position to illuminate the stage. The sections 15 and 16 swing upward on their hinge and pivot to allow the elevation of the projectors to cast light up along section 13. In the latter position, Figure 2, the section 13 is raised 75 and sections 15 and 16 lowered into horizontal alignment and to form a horizontal continuation of the rest of the stage. In this position, the footlights are concealed beneath the stage in inoperative position.

80 The movements of the parts from one position to the other are achieved very easily and swiftly. The mechanisms provide for smooth, and silent changes of position. These mechanisms are simple but prove very efficient 85 and reliable in service. A nice feature is due to the separate formations of the parts, which may be constructed and assembled at low cost and with minimum labor.

90 While the details herein shown are preferred, variations and alterations may be made therein in practice and I desire to be limited only by the state of the prior art and the scope of the appended claims.

Claims:

95 1. An apparatus of the kind described, comprising a stationary stage portion having a well near its front, a movable stage section pivoted to the rear edge of said well, a second movable stage section associated with 100

the front edge of the well, said sections being adapted to be moved into horizontal alignment with the stationary stage, a light projector disposed below the second movable section, and means for simultaneously swinging the first stage section downward on its pivot to a forwardly dipping position and the second stage section and light projector to an elevated position where the projector casts its light up along the first section on to the stage, the light projector being adapted to be disposed in concealed position beneath the movable stage sections when the latter are in horizontal alignment with the rest of the stage.

2. An apparatus of the kind described, comprising a stationary stage portion having a well near its front, a movable stage section pivoted to the rear edge of said well, a second movable stage section associated with the front edge of the well, said sections being adapted to be moved into horizontal alignment with the stationary stage, a light projector disposed below the second movable section, and means for simultaneously swinging the first stage section downward on its pivot to a forwardly dipping position and the second stage section and light projector to an elevated position where the projector casts its light up along the first section on to the stage, the light projector being adapted to be disposed in concealed position beneath the movable stage sections when the latter are in horizontal alignment with the rest of the stage, said means comprising a rocker arm and connecting rods attached to the ends thereof and fastened respectively to the first movable stage section and to the light projector.

3. An apparatus of the kind described comprising a stationary stage portion having a well at its front end, a movable stage section pivoted to the rear edge of the well and means for lowering the movable stage section into a forwardly dipping position and for raising the stage section into horizontal alignment with the stationary stage portion.

4. An apparatus of the kind described comprising a stationary stage portion having a well at its front end, a movable stage section pivoted to the rear edge of the well and means for lowering the movable stage section into a forwardly dipping position and for raising the stage section into horizontal alignment with the stationary stage portion, a light projector positioned to cast its light up along the movable stage section when the latter is lowered.

HOWARD V. HARDING.
